UNITED STATES PATENT OFFICE.

ELMER G. GARTIN, OF CLAREMONT, NEW HAMPSHIRE, ASSIGNOR TO SULLIVAN MACHINERY COMPANY, A CORPORATION OF MASSACHUSETTS.

ROCK-DRILLING DEVICE.

Application filed April 10, 1922. Serial No. 551,326.

My invention relates to rock drilling devices, and more particularly to cleansing fluid supply means for such devices.

An object of my invention is to provide an improved rock drilling device. Another object of my invention is to provide an improved rock drilling device having improved cleansing fluid supply means. A further object of my invention is to provide an improved rock drilling device having improved cleansing fluid supply means and controlling means therefor. A still further object of my invention is to provide an improved rock drilling mechanism having improved combined controlling means for said mechanism per se and for the cleansing fluid supply means associated therewith. Other objects and advantages of my invention will hereinafter more fully appear.

In the accompanying drawings I have shown for purposes of illustration one form which my invention may assume in practice.

In these drawings,

Fig. 1 is a central vertical longitudinal section through a rock drilling mechanism in which the illustrative form of my invention is incorporated.

Fig. 2 is a transverse section on the broken line 2—2 of Fig. 1.

In the accompanying drawings I have shown my invention employed in conjunction with a rock drilling mechanism which includes a motor generally designated 1 and having a cylinder 2 in which a piston 3 is reciprocable under the action of motive fluid supplied thereto in a well known manner under the control of the piston itself. The piston 3 is provided with a striking bar 4 which projects through a front head 5 and suitable ratchet mechanism 6 into a chuck mechanism 7 wherein it engages the rear end of a hollow drill steel 8. The striking bar 4 is provided with grooves 9 to cooperate in a well known manner with the ratchet mechanism 6 and these grooves are made to extend somewhat further back than usual and with a considerable clearance with respect to the lugs which engage them in order that a portion of the motive fluid supplied to the front end of the cylinder 2 may be transmitted through these grooves 9 and so to the hollow steel. The motor 1 is mounted in a well known manner upon a cradle type feed mechanism generally designated 10. Fluid pressure is supplied to

the motor 1 under the control of a throttle valve 11 which is conical in form and is provided with a recess or chamber 12 therewith in which the fluid supply line 13 communicates. The ports by means of which the flow is transmitted from the recess 12 to the rock drilling motor are designated by numerals 12^a and 12^b. A suitable operating handle 14 serves to permit the shifting of the valve 11 to control the supply of fluid to the motor. Coaxially arranged within the valve 11 is an auxiliary valve mechanism generally designated 15 for controlling a supplemental discharge of cleansing fluid to the steel. This mechanism includes a longitudinally extending bore 16 traversing the valve member 11 in which a plunger 17 is longitudinally reciprocable, the plunger 17 carrying at its inner end a valve head 18 which is movable into the chamber 12 and this valve head is adapted to cooperate with a valve seat 19 which is arranged at the mouth of a passage 20 surrounding a reduced portion 21 of the stem 17 and leading to a lateral port 22 in the side wall of the valve member 11. The port 22 is connectible with a passage 23 which leads, as shown in Fig. 1, to the rear end of a cleansing fluid supply tube 24 extending into the bore of the steel. A spring 25 surrounding the rear end of the stem 17 cooperates with a head 26 on the latter to maintain the valve 18 normally closed and a pivoted lever 27 mounted within a longitudinally extending slot in the handle 14 so as to extend in juxtaposition thereto, may be operated by the hand grasping handle 14 to force the valve 18 open as may be desired.

The mode of operation of my improved mechanism will be readily apparent. When the handle 14 is turned to a position to supply motive fluid to the motor 1, the port 22 will be brought in communication with the passage 23, but the valve 18 will prevent the flow of cleansing fluid through the tube 24. During the operation of the motor, however, a quantity of fluid will pass from the front end of the cylinder through the grooves 9 to the chuck and so to the hole to be drilled. When a supplemental stronger blast of air is desired for discharging any accumulation of stone-dust, and chips, or for any other purpose, the lever 27 is operated to force open the valve 18 and fluid will flow from the chamber 12 through the

port 20 to the chamber surrounding the reduced portion 21 and port 22 and passage 23 to the tube 24, and so to the steel. When this supplemental blast is no longer needed, the hand lever 27 may be released. It will thus be obvious that I have provided a very simple and compact device for permitting the discharge of a supplemental blast of cleansing fluid to a steel when desired, and 10 it will be further noted that this same control mechanism could be used in a drill wherein there was no supply through the grooves 9, to occasionally blow out a hole which would not require constant air pressure at all times.

While I have in this application specifically described one form which my invention may assume in practice, it will be understood that this form of the same is shown 20 for purposes of illustration and that the invention may be modified and embodied in various other forms without departing from its spirit or the scope of the appended claims.

25 What I claim as new and desire to secure by Letters Patent is:

1. In a rock drilling mechanism, a drilling motor adapted to actuate a hollow drill steel, cleansing fluid supply means for the 30 drill steel, main controlling means for said motor and said cleansing means including an operating member adapted to be grasped by the operator, and auxiliary means for controlling said cleansing fluid supply means 35 including means located in juxtaposition to said operating member thereby enabling the operator to control said motor and cleansing means by but a single hand without removing said hand from said operating member and with equal facility in all operating 40 positions of the latter.

2. In a rock drilling mechanism, a drilling motor adapted to actuate a hollow drill steel, cleansing fluid supply means for the 45 drill steel, a main controlling valve for said motor and said cleansing means including an operating member adapted to be grasped by the operator, and an auxiliary valve located in said main controlling valve for controlling said cleansing fluid supply means including means for enabling the operator 50 to control said motor and cleansing means by but a single hand without removing said hand from said operating member.

55 3. In a rock drilling mechanism, a fluid actuated drilling motor adapted to actuate a hollow drill steel, cleansing fluid supply means for the drill steel, a main throttle valve having an operating handle adapted 60 to be grasped by the operator, said valve including means for controlling the fluid flow to both said motor and cleansing means, and auxiliary controlling means for enabling the operator to control the fluid flow to said 65 cleansing fluid supply means comprising

a member located in juxtaposition to said handle and adapted to be grasped by the same hand without removing said hand from said main valve operating handle and with equal facility in all operating positions 70 of the latter.

4. In a rock drilling mechanism, a fluid actuated drilling motor adapted to actuate a hollow drill steel, cleansing fluid supply means for the drill steel, a main throttle 75 valve having an operating handle adapted to be grasped by the operator, said valve including means for controlling the fluid flow to both said motor and cleansing means, and auxiliary controlling means for enabling 80 the operator to control the fluid flow to said cleansing fluid supply means having an operating handle overlying said main valve operating handle and adapted to be included within the grasp of a single hand without 85 removing said hand from said main valve operating handle.

5. In a rock drilling mechanism, a fluid actuated drilling motor adapted to actuate a hollow drill steel, cleansing fluid supply 90 means for the hollow drill steel, a main valve having an operating handle adapted to be grasped by the operator, said valve including means for controlling the fluid flow to both said motor and cleansing means, and an auxiliary valve embodied within 95 said main valve and constituting means for enabling the operator to control the fluid flow to said cleansing fluid supply means, and an auxiliary control handle therefor positioned to be grasped by but a single hand without removing said hand from said 100 main valve operating handle.

6. In a rock drilling mechanism, a fluid actuated drilling motor adapted to actuate 105 a hollow drill steel, cleansing fluid supply means for the hollow drill steel, a main valve having an operating handle adapted to be grasped by the operator, said valve including means for controlling the fluid flow to both said motor and cleansing means, and an auxiliary valve arranged within said 110 main valve and having an operating handle overlying said main valve operating handle for enabling the operator to control the fluid 115 flow to said cleansing fluid supply means, said handles being within the grasp of a single hand without removing said hand from said main valve operating handle.

7. In a rock drilling mechanism, a fluid actuated drilling motor comprising a cylinder and a percussive piston reciprocable 120 therein, means operative to supply cleansing fluid from said cylinder to a hollow drill steel during the running of said motor, means for supplying an auxiliary supply of 125 cleansing fluid to the drill steel comprising a fluid supply tube terminating at one end within the drill steel, a main valve having means for controlling the fluid flow to said 130

motor and to both of said cleansing means and having a manually operable grasping handle, and auxiliary means including a valve for separately controlling the fluid flow to said auxiliary cleansing means, said auxiliary means having an operating member arranged in juxtaposition to said main throttle valve handle so as to enable the operator to operate both valves by but a single hand without removing said hand from said main valve handle and with equal facility in all operating positions of the latter.

8. A controlling valve mechanism for a rock drilling motor and drill steel cleansing means comprising a casing having fluid passages formed therein leading respectively to said motor and said steel cleansing means, a main controlling valve arranged within said casing and having means for controlling said passages, said valve having an operating handle, an auxiliary valve arranged coaxially within said main valve and movable axially relative thereto for controlling the passages leading to said cleansing means and having an operating handle pivoted on said main valve operating handle, said auxiliary valve being adapted to be opened when said handles are pressed together and automatically closed when said handles are released.

30 9. A controlling valve mechanism for a rock drilling motor and drill steel cleansing means comprising a casing having fluid passages formed therein leading respectively to said motor and said steel cleansing means, a main controlling valve arranged within said casing including means for controlling the fluid flow in said passages, said valve having a fluid pressure chamber formed therein and an operating handle, an auxiliary valve arranged coaxially within said main valve and disposed in said fluid pressure chamber for controlling the passage leading to said cleansing means, means for moving said auxiliary valve relatively to said main valve to open position, and means for automatically closing said auxiliary valve.

10 10. A controlling valve mechanism for a rock drilling motor and drill steel cleansing means comprising a casing having fluid passages formed therein leading respectively to said motor and said steel cleansing means, a ported valve bushing arranged within said casing, a main controlling valve arranged within said bushing and including means for controlling the fluid flow in said passages, said valve having an operating handle, an auxiliary valve arranged coaxially within said main valve and including means for

controlling the fluid flow in the passages leading to said cleansing means, said auxiliary valve having an operating handle overlying said main valve operating handle, and means for opening said auxiliary valve when said handles are pressed together.

11. A controlling valve mechanism for a rock drilling motor and drill steel cleansing means comprising a casing having passage means formed therein leading to said motor and steel cleansing means, a ported valve bushing arranged in said casing, a main valve arranged in said bushing and including means for controlling the fluid flow to said motor and cleansing means, and an auxiliary valve arranged coaxially within said main valve and adapted to control the fluid flow to said cleansing means, said auxiliary valve including means for automatically seating the same.

12. In a rock drilling mechanism, a fluid actuated motor adapted to actuate a hollow drill steel, said motor including means for supplying cleansing fluid to the drill steel during running thereof, supplemental cleansing means for the drill steel, a main valve having a manually graspable operating handle including means for controlling the fluid flow to said motor and both of said cleansing means, and an auxiliary valve including means for controlling the fluid flow to said supplemental cleansing means, said auxiliary valve having an operating member arranged in juxtaposition to said main valve handle so as to enable the operator to operate both valves by but a single hand without removing said hand from said main valve handle and with equal facility in all operating positions of the latter.

13. In a rock drilling mechanism, a fluid actuated motor adapted to actuate a hollow drill steel, cleansing fluid supply means for the drill steel, a main valve having means for controlling the fluid flow to said motor, said valve having a handle adapted to be grasped by the operator, and a separate valve for controlling the fluid flow to said drill steel cleansing means, said valve being movable independently of said main valve and having an operating handle arranged in juxtaposition to said main valve handle so as to enable the operator to operate both valves by but a single hand without removing said hand from said main valve handle and with equal facility in all operating positions of the latter.

In testimony whereof I affix my signature.
ELMER G. GARTIN.
